Primary Examiner — Wendy L Arminio*Assistant Examiner* — Maheen Khurshid(74) Attorney, Agent, or Firm — Bridgeway IP Law Group, PLLC; Sang Ho Lee; Hyun Woo Shin(57) CLAIM

I claim the ornamental design for a mask, as shown and described.

DESCRIPTION

FIG. 1 is a perspective view of a mask, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another right side view thereof showing a configuration of use in which the mask is folded in half.

1 Claim, 5 Drawing Sheets(56)
